UNITED STATES PATENT OFFICE

LEO ROSEMAN, OF NEWARK, NEW JERSEY

SEWING MACHINE

Application filed March 19, 1928. Serial No. 262,648.

This invention relates, generally, to improvements in sewing machines; and the same has reference, more particularly, to a novel construction and arrangement of means for controlling the movement of fastener provided tape to and at the sewing point of the machine, to assure accurate placing of the attaching stitches relative to metallic fasteners of the tape, whereby the machine needle will skip the sides of the latter when stitching across the same to sew the tape to garment bodies.

The present invention has for an object to provide a modified construction of mechanism which is generally similar to that shown in my copending application for Letters Patent of the United States, Ser. No. 249,028, filed January 24, 1928, but differs therefrom in that the means to assure a controlled movement of the fastener tape to the stitching or sewing point comprises an automatically actuated push-finger which is caused to engage each fastener of the tape as it is advancing toward the sewing point, and thereupon to push the same to a predetermined position whereby any tendency of the tape to underfeed is compensated for, so that the proper number of stitches between and traversing the fasteners will be made, while at the same time a governing effect is exercised upon the ordinary work-feeding means of the sewing machine mechanism so that uniform operation of the latter is assured regardless of whether the work operated upon is heavy or light, i. e. thick or comparatively thin.

Another object of the invention is to provide a modified arrangement and operation of means located at the sewing point of the machine, whereby each fastener is moved to a predetermined position relative to the reciprocating sewing needle, so that the traversing of the formed stitches across the metal parts of the fasteners without contact therewith is also assured and consequently risk of breaking the needle or damaging the fasteners is avoided; this modified means being an alternative for that shown and described in my aforesaid copending application for patent.

Other objects of the present invention, not at this time more particularly enumerated, will be clearly understood from the following detailed description of the same.

The present invention is illustrated in the accompanying drawings, in which:—

Figure 1 is a plan view and Figure 2 is a front side elevation of the mechanism for controlling the movement of fastener tape relative to the sewing point of the sewing machine in which said mechanism is incorporated. Fig. 3 is a fragmentary detail view of the usual stitch forming and work feeding means of the sewing machine.

Similar characters of reference are employed in the said views, to indicate corresponding parts.

Referring now to said drawings, the reference character 10 indicates the bed-plate of a sewing machine, preferably of the general type and kind shown and described in my heretofore mentioned copending application for patent, and from the main shaft of which is driven the vertical shaft 24 for actuating the particular tape controlling mechanism with which the instant invention deals.

Secured upon the bed-plate 10, and aligned to the path of movement of fastener tape (which is indicated in Figure 1 by dot and dash lines) over the same toward the stitching and work feeding mechanism of the machine (constituted by the presser foot *a*, feed dog *b*, needle *c* and looper *d*—see Fig. 3), is a guide plate 16 to overhang one side of the fastener tape, and serving to provide, in cooperation with a second guide member 17 at the opposite side of the tape, a guideway through which the tape passes toward the stitching point of the machine. The tape is provided with metallic fasteners at spaced intervals, eye-loops 20 being illustrated in connection therewith. Usually the eye-loops 20 are spaced one inch apart, and the sewing mechanism is adjusted to produce a predetermined number of stitches per inch calculated to extend between and traverse the eye-loops. The spacing of the fasteners on the tape and the number of stitches to be sewn between and over the fasteners is subject to more or less variation, and it will

be understood that the mechanism may be adjusted and arranged in any given case to correspond to any selected arrangement in these respects.

5 In practice the eye tape is first passed through a delivery feed and control mechanism whereby the same is drawn from a roll thereof (not shown) and then passed through the guide means 16—17; the garment to which the tape is to be sewn being fed over the same and intermediate the presser foot and feed-dog of the sewing mechanism in the usual manner well understood by those familiar with sewing machine construction 10 or operation.

Fixed on said bed-plate 10 is a bearing frame 25 provided with transversely aligned bearings 26 in which is journaled a transverse shaft 27. Said transverse shaft 27 is 15 driven from said vertical shaft 24 by means of intermeshing screw-gears 28 and 29, respectively fixed on said vertical and transverse shafts.

The delivery feed and control mechanism 20 comprises a bearing bracket fixture 30 which is fixed on the bed plate to overhang the front side thereof. Journaled in said bearing bracket is a lay shaft 31. This lay shaft 31 is driven from said transverse shaft 27 by 25 means of intermeshing screw-gears 32 and 33 respectively fixed on said transverse and lay shafts. Fixed on the outer end of said lay shaft 31, so as to be rotated thereby, is a feed roller 34, constituting one of a pair of such 30 rollers. Connected with said bearing bracket 30, in a manner preferably corresponding to that disclosed in my heretofore mentioned patent application, is a bearing arm 35, in the upper end of which is journaled a spindle 36, and fixed on the outer end of said spindle is a feed roller 37, constituting the second of said pair of such rollers, the same being 35 adapted to oppose and cooperate with said feed roller 34. Said second feed roller 40 is driven in an opposite direction to the feed roller 34 by means of intermeshing spur gears 38 and 39 respectively fixed on said lay shaft 31 and spindle 36. Said second feed roller 37 is preferably annularly grooved as 45 shown to provide clearance space for the passage of the metallic eyes 20 of the fastener tape T, as the latter is moved through and between the pair of rollers 34 and 37. The tape engaging faces of said rollers 50 34—37 are preferably roughened, as by knurling, to better grip the tape when operatively engaging and feeding the same.

The means for governing or controlling the advance of the tape as it moves toward the sewing point of the machine, the operation and advantages of which will be hereinafter more fully set forth, comprises timed means to engage each eye of the tape in such manner as to produce a forward compensatory thrust or push upon the tape adapted

to compensate for any tendency of the latter to lag or otherwise make improperly timed advance under the normal intermittent action of the feed and stitch forming mechanism of the sewing machine, so that a uniform properly controlled movement of the tape and its fasteners to the stitching or sewing point of the machine is assured, to the end that the selected number of stitches sewn between and across the fasteners of the tape 70 will be produced. Connected with the horizontal portion of said bearing bracket fixture 30 is a slideway 40 in which is housed, for both longitudinal reciprocation and for limited oscillation, a push-bar 41 having at 75 its free forward end a push-finger 42 suitably shaped to engage the rear sides of the eyes 20 of the tape T. Said push-bar 41 is provided intermediate its ends with an upwardly extending pivot stud 43 which project through a slot 44 formed in said bearing bracket fixture 30. Secured upon said bearing bracket fixture 30 is a housing member 45, in the forward end of which is slidably disposed a push-piece 46 adapted to bear against said pivot stud 43. Within said housing member 45 is a compression spring 47 backed by a threaded plug 47' secured in the rearward end of said housing member. Said spring thrusts against said push-piece 46, which in turn thrusts forwardly on the pivot stud of the push-bar 41 thus biasing the latter to forwardly thrust operative position relative to the fasteners or eyes 20 of the tape T. The push-bar 41 is tapered both 90 forwardly and rearwardly from said pivot stud 43 so as to be capable of limited turning movement in horizontal plane about the axis of said pivot stud. Secured on the rear end of said push-bar 41 is a rocker stud 48. A 95 spring device 49 has one arm arranged to bear tensionally against said roller-stud 48 in such manner as to bias said push-bar so as to position its forward end in normally 100 rearwardly swung position, with a side portion 41' stopped against the adjacent side of the slideway 40.

The means for automatically producing timed actuation of said push-bar 4, whereby its push-finger 42 may be projected into and withdrawn from the path of movement of the eyes of the tape as required, and, when properly related to the latter, oscillated at proper times to transmit to the tape the desired governing or compensating forward thrust or push, preferably comprises the following devices:—

Connected with said housing 45 is an upwardly and rearwardly extending supporting arm 50, and pivotally connected with the free end of said arm is a depending lever member 51. Said lever member is provided at its lower free end with a rearwardly turned portion 52 adapted to engage the forward side of said roller stud 48. Said lever member is 125

further provided with an off-set portion 53 which carries a laterally projecting roller stud 54. Fixed on said transverse shaft 27 is a cam wheel 55 having a peripheral structure adapted to provide a high cam-portion 56 and a low cam portion 57, which, when the cam wheel is rotated engages said roller stud 54 to actuate said lever member 51. The high cam-portion 56, when operative, swings rearwardly said lever member 51 thereby retracting the push-bar 41 against the compression of the spring 47, thus withdrawing the push-finger 42 from the path of movement of the eyes 20 of the tape T. The low cam-portion 57, when operative, permits the lever member 51 to swing forward, whereby the tension of the spring 47 thrusts forward the push-bar 41 to operatively position its push-finger 42 so that it may engage behind an eye 20 of the tape T.

The means for oscillating the push-bar 41 when its push-finger 42 is engaged behind an eye 20 of the tape T comprises a cam wheel 58 having a laterally projecting cam portion 59 which engages the side of the roller stud 48, thereby turning the push-bar 41 on its pivot 43 and against the tension of the spring 49, thus causing the push-finger 42 to be swung forwardly to in turn push or thrust forward the engaged eye 20 to thereby compensatingly advance the tape toward the sewing point of the machine.

Arranged adjacent to the sewing point of the machine is a primary control mechanism adapted to positively position each eye so as to assure proper relation of the same to the reciprocating needle of the sewing mechanism whereby, as the work is advanced by the feed of the machine, all risk of contact of the needle with the eye is avoided, and properly traversing stitches with respect to each individual eye is obtained. This primary control mechanism may consist in the positive stop or eye arresting form thereof shown and described in my aforesaid copending application for United States Letters Patent. As an alternative to such form of primary control means I have shown in the instant case a modified arrangement whereby each eye of the tape, as it arrives adjacent to the sewing point, is pushed into proper position relative to the reciprocating sewing needle. This alternative form of primary control mechanism comprises a housing 60 pivotally mounted on the bed-plate 10 to extend toward the fastener bordered margin of the tape T and adjacent to the stitching or sewing point of the machine. The means for pivoting the housing 60 comprises a bearing bracket 61 secured on the bed-plate 10 to overhang the housing so as to receive the pivot stud 62 with which the latter is provided. The forward end of the housing 60 is normally disposed and yieldably held in rearwardly swung position, as determined by an adjustable stop 63 fixed on

said bed-plate 10, by means of a pull-spring 64. Slidably related to and carried by said housing 60 is a thrust-bar 65 having a tail-piece 66 projecting exteriorly from the rearward end of said housing. Adjacent to the rearward end of said housing 60 is a bearing support 67, forming a part of the bearing frame 25, in which is pivotally supported a depending lever arm 68 the free end of which is operatively coupled with the tail-piece 66 of said thrust-bar 65. A compression spring 69 is arranged intermediate said lever arm 68 and a stationary part of said bearing frame 25 to normally thrust said lever arm and the engaged thrust-bar 65 forwardly into operative relation to the eyes 20 of the tape T. Fixed on said transverse shaft 27, so as to be rotated thereby, is a cam wheel 70 having suitable circumferential cam formations which operatively engage a roller stud 71 carried by said lever arm 68, thereby producing properly timed retraction of the thrust-bar 65.

The thrust-bar 65 is provided at its forward free end with a thrust-finger 65' suitably shaped to engage the rearward sides of the eyes 20 of the tape T. The means for swinging the housing 60 so as to impart a forward thrusting or pushing movement of the thrust-finger 65', when operatively engaged with an eye 20 of the tape T, to thereby positively dispose said eye in proper relation to the reciprocating sewing needle, comprises an up-standing support 72 fixed on the rearward portion of said housing 60 in which is adjustably mounted a laterally projecting nosing 73. Fixed on said transverse shaft 27, so as to be rotated thereby, is a cam wheel 74 provided on a side face thereof, which is opposed to said nosing 73, with a cam-portion 75 adapted at properly timed intervals to engage said nosing 73 to swing rearward the rear portion of said housing 60 to thereby turn the same on its pivot to in turn swing forward the front end of said housing, thus carrying the thrust finger 65' into forwardly thrusting engagement with an eye 20 about to be traversed by the sewing needle, whereby said eye is properly disposed in relation to the movements of the latter.

In the operation of the machine, the tape T is led from a supply reel (not shown) between the auxiliary feed roller 34-37 and thence through the guides 16-17 to pass between the presser foot and feed dog devices of the sewing mechanism (not shown); the garment being also fed with the tape between said presser foot and feed dog in the usual manner. The auxiliary feed rollers 34-37 are timed to feed the tape at slightly less speed than the feed of the sewing mechanism will advance the work to produce the desired number of stitches between and over the eyes 20. The advance of the tape to the sewing point, however, is governed and controlled by the automatic timed actuation of

the push-bar 41, which, as each eye 20 of the tape comes adjacent thereto, is first retracted to allow the eye to pass and then project to a position behind the advanced eye, whereupon the means for oscillating the push-bar 41 operates to swing the same on its pivot 43 so that the push-finger 42 will engage the rear side of the advanced eye 20 and will thrust the same forward, the tape T under such circumstances slipping through the feed rollers 34-37. It will thus be apparent that as each eye advances the tape will be compensatingly thrust forward to the desired extent required to assure of positively controlled and uniformly governed advancing movement of the tape and its eyes under the operation or pull of the main feed devices of the sewing mechanism. The tape thus governed and controlled, so that its advancing movement will be such as to prevent either overfeeding or underfeeding by the feed of the sewing mechanism, assures that the desired number of stitches extending between and over the eyes will be produced at the sewing point. The eyes of the tape may be suitably manipulated at the sewing point so that proper disposition of the same relative to the reciprocating sewing needle will be assured, either by the means shown in my aforesaid copending application for United States patent, or by the means herein shown and described. When utilizing the latter means, the operation is as follows:—

As each eye approaches the sewing point, the thrust bar 65 is first retracted to allow the eye to pass, and is then projected to dispose the thrust finger 65' behind the eye, so that preparatory to the formation of stitches across the sides of the eye, the housing of the thrust bar 65 may be oscillated or turned on its pivot, to thereby swing forward the thrust-finger 65' so as to engage behind and to thereupon push forward the eye so as to dispose the same in a proper position relative to the descent of the sewing needle preparatory to the making of the stitches which traverse said eye; these operations being repeated as each eye approaches the sewing point.

It will be obvious from the above description, that the instant invention relates to a modified form or different species of fastener tape control mechanism for sewing machines very similar in general principles to that disclosed in my copending application above referred to, except that instead of operating to control the movement of the tape and its eyes by providing a positive stop which arrests or holds the eyes and tape in the desired predetermined positions, as in the latter case, I here provide means which positively pushes or advances the tape and its eyes in such manner as to assure first, the governed movement of the tape to the sewing mechanism and, secondly, the controlled placing of each eye

relative to the movement of the sewing needle prior to the production of stitches traversing said eyes.

I am aware that many changes may be made in the general arrangements and combinations of the various devices and parts making up the species of fastener tape control means for sewing machines according to the instant invention, as well as in the details of the construction of the same, without departing from the spirit of this invention. Hence, I do not limit myself to the exact arrangements and combinations of the various devices and parts as set forth in the foregoing specification, nor do I confine myself to the exact details of the construction of said parts as illustrated in the accompanying drawings.

I claim:—

1. In combination with a sewing machine having stitch forming means including a work feed, auxiliary means for feeding fastener tape to said stitch forming means at slightly less speed than the work is normally moved by the work feed, and positive pushing means cooperative with the fasteners of the tape for governing the movement of the tape from said auxiliary feeding means to said stitch forming means.

2. In combination with a sewing machine having stitch forming and work feeding means and adapted to stitch through tape having metallic fasteners thereon, fastener positioning means operative to predetermine the position of each fastener relative to the stitch forming means prior to the formation of stitches traversing the same, auxiliary means for feeding the fastener tape to said stitch forming means at slightly less speed than the work is normally moved by the work feeding means, and positive pushing means cooperative with the fasteners of the tape for governing the movement of the tape from said auxiliary feeding means to said stitch forming means.

3. In combination with a sewing machine having stitch forming means including a primary work feeding means, auxiliary means for feeding tape having metallic fasteners to said stitch forming means and primary feeding means operative to advance the tape at slightly less speed than the work is normally moved by the primary work feeding means, and means for governing the movement of the fastener tape from said auxiliary feeding means to said primary feeding means, comprising a push-bar, means to operatively position the said push-bar relative to each fastener of the tape as the latter advances between said auxiliary and primary feeding means, and means to move said push-bar with forward thrusting effect upon said tape and its fasteners.

4. In combination with a sewing machine having stitch forming means including a pri-

mary work feeding means, auxiliary means for feeding tape having metallic fasteners to said stitch forming means and primary feeding means operative to advance the tape at slightly less speed than the work is normally moved by the primary work feeding means, fastener positioning means operative to predetermine the position of each fastener relative to the stitch forming means prior to the formation of stitches traversing the same, and means for governing the movement of the fastener tape from said auxiliary feeding means to said primary feeding means, comprising a push-bar, means to operatively position the push-bar relative to each fastener of the tape as the latter advances between said auxiliary and primary feeding means, and means to move said push-bar with forward thrusting effect upon said tape and its fasteners.

5. In combination with a sewing machine having stitch forming means including a primary work feeding means, auxiliary means for feeding tape having metallic fasteners to said stitch forming and primary feeding means operative to advance the tape at slightly less speed than the work is normally moved by the primary work feeding means, fastener positioning means operative to predetermine the position of each fastener relative to the stitch forming means prior to the formation of stitches traversing the same, said latter means comprising a thrust-bar, means to operatively engage said thrust-bar behind a fastener approaching said stitch forming means, and means to move said thrust-bar to dispose the engaged fastener in desired predetermined position; and positive pushing means cooperative with the fasteners of the tape for governing the movement of the tape from said auxiliary feeding means to said primary feeding means.

6. In combination with a sewing machine having stitch forming means including a primary work feeding means, auxiliary means for feeding tape having metallic fasteners to said stitch forming and primary feeding means operative to advance the tape at slightly less speed than the work is normally moved by the primary work feeding means, fastener positioning means operative to predetermine the position of each fastener relative to the stitch forming means prior to the formation of stitches traversing the same, said latter means comprising a thrust-bar, means to operatively engage said thrust-bar behind a fastener approaching said stitch forming means, and means to move said thrust-bar to dispose the engaged fastener in desired predetermined position; and means for governing the movement of the fastener tape from said auxiliary feeding means to said primary feeding means, comprising a push-bar, means to operatively position the push-bar relative to each fastener of the tape as the latter advanc-

es from said auxiliary feeding means, and means to move said push-bar with forward thrusting effect upon said tape and its fasteners.

7. In combination with a sewing machine having stitch forming and work feeding means adapted to stitch through tape having metallic fasteners thereon, fastener positioning means operative to predetermine the position of each fastener relative to the stitch forming means prior to the formation of stitches traversing the same, said latter means comprising a thrust-bar, means to operatively engage said thrust-bar behind a fastener approaching said stitch forming means, and means to move said thrust-bar to dispose the engaged fastener in desired predetermined position.

8. In combination with a sewing machine having stitch forming and work feeding means adapted to stitch through tape having metallic fasteners thereon, auxiliary means for feeding said tape to said stitch forming means at slightly less speed than the work is normally moved by the work feeding means, fastener positioning means operative to predetermine the position of each fastener relative to the stitch forming means prior to the formation of stitches traversing the same, said latter means comprising a thrust-bar, means to operatively engage said thrust-bar behind a fastener approaching said stitch forming means and means to move said thrust-bar to dispose the engaged fastener in desired predetermined position.

In testimony that I claim the invention set forth above I have hereunto set my hand this 17th day of March, 1928.

LEO ROSEMAN.
